UNITED STATES PATENT OFFICE

144,166

DESIGN FOR A ROTOR FOR A WINDMILL

Stanley R. Du Brie, Detroit, Mich.

Application October 4, 1944, Serial No. 115,611

Term of patent 14 years

(Cl. D55—1)

To all whom it may concern:

Be it known that I, Stanley R. Du Brie, a citizen of the United States, residing at Detroit 14, in the county of Wayne and State of Michigan, have invented a new, original, and ornamental Design for a Rotor for a Windmill, of which the following is a specification, reference being made to the accompanying drawings, forming part thereof.

Fig. 1 is a perspective view of a rotor for a windmill showing my new design;

Fig. 2 is a top plan view, and

Fig. 3 is a side elevation of the same.

I claim:

The ornamental design for a rotor for a windmill, substantially as shown.

STANLEY R. DU BRIE.
